C. W. METZGAR

COMPRESSOR UNLOADER

Filed Nov. 3, 1925

UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed November 3, 1925. Serial No. 66,496.

This invention relates to compressors, but more particularly to an unloader for compound compressors capable of also acting as a starting unloader.

5 The objects of the invention are to secure simple and efficient means for unloading the high and low pressure cylinders of a compound compressor by means of by-pass connections between the inlet and discharge 10 passages of the cylinders so that both cylinders discharge into the intake passage of the low pressure cylinder for unloading purposes. The advantage of unloading into the intake passage of the low pressure cylinder 15 resides in the fact that the noise is greatly reduced and the unloading is made almost silent.

The construction and arrangement of the 20 by-pass unloading connections affords a ready and convenient means for locating the unloading valves in said connections in such manner that small space is taken up on the compressor cylinders in case said valves are mounted on the cylinders which is the preferable 25 construction. For starting purposes, in case there is no pressure in the receiver, the unloading valves may be maintained closed either by hand operated devices or by a valve controlling the automatic connections from the receiver to an auxiliary 30 valve, which is normally responsive to receiver pressure for maintaining the unloader valves closed.

The invention is shown in one of its preferred forms in the accompanying drawing 35 which is a diagrammatic representation partly in longitudinal sectional elevation and partly broken away of the unloader.

Referring to the drawing, the low pressure cylinder A and the high pressure cylinder B are in this instance provided with a trunk piston C having the connecting rod D and adapted to be driven in any suitable manner, as for instance by means of an oil engine. The drawing is intended to indicate 40 an oil engine driven compressor.

The low pressure cylinder A is provided with the inlet valve or valves E and the discharge valve or valves F of which there may

be any desired number of any suitable type, 50 as for instance, plate valves. The intake G of the low pressure cylinder communicates with the intake passage H and the discharge passage J for said cylinder communicates with the passage K leading to the intercooler 55 L. The passage O from the intercooler communicates through the intake passage P of the high pressure cylinder with the high pressure intake valve or valves Q. The discharge passage R of the high pressure cylinder is provided with the discharge valve or valves S and is connected to the receiver T by the usual pipe U.

A by-pass connection V is formed in the head of the low pressure cylinder A connecting the discharge passage J with the inlet passage H and in this by-pass connection is located an unloading valve W of any suitable form which may be both manually and automatically controlled. A by-pass connection X is also provided in the cylinder walls from the high pressure cylinder B to the discharge passages J and K and a similar unloading valve Y both manually and automatically controlled is provided at this 70 point so that when both unloading valves W and Y are open both high and low pressure cylinders are unloaded and discharge through said by-pass connections and unloader discharge passages to the intake G of 80 the compressor.

The unloading valves W and Y comprise the valve seats a having the guides b between which and the valves are located the compression springs c. The valve casings d contain the plungers e having the stems f bearing on the valves and hand wheels g forming manual means for closing the unloading valves and maintain them closed when desired.

An auxiliary valve Z responsive to receiver pressure from the pipe h and connected by the pipes j and k to the valve casings d at the points o and p respectively, moves the plungers e inwardly due to receiver pressure and maintains the unloading valves closed under normal conditions. Release of pressure from the plungers e of the

unloading valves causes the unloading valves to open.

The auxiliary valve Z is provided with a casing q having the valve member r formed with the heads s and t and carrying the shoe u which controls the fluid pressure port v and the atmospheric port w. The space x is always subject to receiver pressure and a compression spring y tends to move the valve member r to a position to open the space x to the port v and admit receiver pressure through the pipes j and k for closing the unloader valves. A pressure fluid connection z from the pipe h to the chamber 3 in the auxiliary valve casing supplies pressure through the small port 4 against an opposite head t of the valve member r to force the valve member in the opposite direction to the position indicated in the drawing, in which the shoe u connects the ports v and w so that pressure is released from the plungers e through the atmospheric port w and the unloader valves are permitted to open under the influence of the valve springs e as indicated in the drawing. A leak port 5 is in the casing q and a diaphragm 6 carrying a needle valve 7 is located in the chamber 3. A spring 8 above the diaphragm 6 is regulated by the set screw 9 so that the needle valve 7 normally closes the small port 4 and upon an increase of pressure in the receiver beyond a predetermined point, the diaphragm 6 retracts the needle valve 7 and opens the small port 4 admitting receiver pressure against the valve head t to force the valve to the position indicated in the drawing connecting the ports v and w. Upon reduction of receiver pressure to a predetermined point the diaphragm 6 closes the port 4 by means of the needle valve 7 and due to the leak port 5 the spring y actuates the valve member r.

A three-way cock 10 or other suitable device is provided in the receiver pressure line h for starting purposes, when starting the compressor under discharge line pressure. If there is no pressure in the discharge line, the unloading valves W and Y will be open when starting, but for starting under discharge line pressure the three-way cock 10 is turned to release the pressure against the unloader valve plungers e and permit the unloading valves to open and remain open until the engine comes up to speed, at which time the unloading valves W and Y are closed by the hand wheels g until pressure is built up in the receiver. The hand wheels are then backed off so that the unloading valves will operate automatically from the auxiliary valve Z.

In the operation of the device, let it be assumed that there is pressure in the receiver T and the compressor is running normally. An increase of pressure in the receiver T beyond the predetermined point

will cause the needle valve 7 of the auxiliary valve Z to open the port 4 and cause the valve member r to assume the position shown in the drawing so that pressure is relieved from the unloading valve plungers e and the unloading valves W and Y automatically open for unloading the cylinders, through the by-pass connections described and upon a reduction of pressure in the receiver to a predetermined point the unloading valves will automatically close.

I claim:

1. In a compound compressor, the combination of high and low pressure cylinders, inlet and discharge valves therefor, an inter-cooler, a by-pass connection in the wall of the low pressure cylinder connecting the inlet and discharge passages of said cylinder, an unloading valve located in and controlling said by-pass connection, whereby the low pressure cylinder discharges through the discharge valves and said by-pass connections into the intake passage for unloading when the unloading valve is open, a second by-pass connection in the wall of the high pressure cylinder leading from the high pressure cylinder to the discharge passage of the low pressure cylinder, and an unloading valve located in and controlling said second by-pass connection, whereby the high pressure cylinder also discharges into the intake passage of the low pressure cylinder for unloading when both unloading valves are open.

2. In a compound compressor, the combination of high and low pressure cylinders, inlet and discharge valves therefor, an inter-cooler, a by-pass connection in the wall of the low pressure cylinder connecting the inlet and discharge passages of said cylinder, an unloading valve located in and controlling said by-pass connection, whereby the low pressure cylinder discharges through the discharge valves and said by-pass connection into the intake passage for unloading when the unloading valve is open, a second by-pass connection in the wall of the high pressure cylinder leading from the high pressure cylinder to the discharge passage of the low pressure cylinder, an unloading valve located in and controlling said second by-pass connection, whereby the high pressure cylinder also discharges into the intake passage of the low pressure cylinder for unloading when both unloading valves are open, a second by-pass connection in the wall of the high pressure cylinder leading from the high pressure cylinder to the discharge passage of the low pressure cylinder, an unloading valve located in and controlling said second by-pass connection, whereby the high pressure cylinder also discharges into the intake passage of the low pressure cylinder for unloading when both unloading valves are open, and automatic means responsive to receiver pressure for automatically controlling both of said unloading valves for both cylinders.

3. In a compound compressor, the combination of high and low pressure cylinders, inlet and discharge valves therefor, an inter-cooler, a by-pass connection in the wall of the high pressure cylinder leading from the high pressure cylinder to the discharge pas-

sage of the low pressure cylinder, an unloading valve located in and controlling said second by-pass connection, whereby the high pressure cylinder also discharges into the intake passage of the low pressure cylinder for unloading when both unloading valves are open, and combined manual and pres-

sure fluid automatically actuated means for controlling said unloading valves for both cylinders.

In testimony whereof I have signed this specification.

CHESTER W. METZGAR.
